UNITED STATES PATENT OFFICE.

ERNEST CLARK, OF ABINGTON, MASSACHUSETTS, ASSIGNOR TO ABINGTON TEXTILE MACHINERY WORKS, OF BOSTON, MASSACHUSETTS, A TRUST OF MASSACHUSETTS.

VACUUM STRIPPER FOR CARDING ENGINES.

Application filed January 30, 1925. Serial No. 5,748.

The invention applies in connection with the traversing stripper-nozzles of vacuum stripping mechanisms for carding engines.

The invention is illustrated by the accompanying drawings, in which a representative embodiment of the said features is shown.

Fig. 1 is a perspective view of certain portions of a carding engine, and of a vacuum stripper mechanism arranged to cooperate with the main cylinder and doffer-cylinder of the carding engine, with the invention incorporated in connection with the stripper-nozzles. The gear-box 6 is broken away partly in this view.

Fig. 2 is a side elevation of the three-way piece or suction-box and doffer-nozzle, detached, on a larger scale than Fig. 1.

Fig. 3 is a plan view of the parts which are shown in Fig. 2.

Fig. 4 is a partly sectional plan view of certain details in connection with the cylinder-nozzle.

Portions of the main cylinder and doffer of a carding engine are indicated at 1 and 2, Fig. 1. At 3 is indicated a portion of the removable door which forms a part of the cylinder casing in the angle between the cylinder and doffer, just above the doffer. At 4 is indicated a portion of supporting frame-work at one end of the doffer, and at 5 a portion of the guard enclosing the doffer-gear (not shown). At 6 is a gear-box, resting upon the doffer-gear guard, and partially enclosing the spur-gears 7 and 8 by means of which rotary motion is transmitted from the doffer-gear to the traverse-screw (not shown), enclosed within the stationary traverse-tube 9, and cooperating with the nozzle-carriage 10 to cause the said carriage to travel from one side of the carding engine to the other side thereof, so as to traverse the cylinder-stripping nozzle 11 and doffer-stripping nozzle 12 along the peripheries of the cylinder and doffer, respectively, from end to end of the cylinder and doffer.

At 13 is a so-called three-way piece, constituting what may be termed a suction-box, which is mounted upon the stripper-carriage, and to which is attached one end of the suction-pipe 14, Fig. 1. To the said three-way piece or suction-box are attached the two nozzles, 11 and 12. The nozzle 11 extends rearwardly from the three-way piece toward the cylinder, its mouth-end being entered into a slot 31 in door 3, the said slot

extending horizontally lengthwise of the cylinder, so that the said end of the cylinder-nozzle works close to the face of the card-clothing of the cylinder. The doffer-nozzle 12 extends downward from the three-way piece alongside a fixed bar 15, Fig. 1, extending lengthwise of the doffer, above the latter, the mouth-end of such nozzle working close to the face of the card-clothing of the doffer. This construction constitutes a combination nozzle device which is adapted to strip both the cylinder and the doffer at the same time.

Traverse-tube 9 is mounted in parallelism with the surfaces of the card-clothing of the main cylinder 1 and doffer 2, respectively, and consequently as the nozzle-carriage 10 travels across the width of the carding engine, the mouths of the two nozzles 11 and 12 move in paths which are parallel with the said surfaces.

In accordance with the invention, the three-way piece 13 is secured detachably to the carriage 10 by means of clamping screws 16, 16, Fig. 1, occupying slots 17, Fig. 2, in a plate 18 extending downward from the body of the three-way piece, the stems of such screws entering threaded holes that are tapped in the carriage 10. The screws 16, 16, clamp one face of the said plate against a face of the carriage. In order to provide for adjustment of the doffer-nozzle for the purpose of locating its mouth-end closer to or farther from the surface of the card-clothing of the doffer, the slots 17 are made elongated. In order to prevent the three-way piece from assuming a laterally-inclined position, the plate 18 is formed with a vertical rib or tongue 19, Fig. 2, and a corresponding groove is formed in the opposing face of the carriage 10 which is occupied by the said rib or tongue. This rib or tongue, and the groove, constitute guiding means to keep the elongated mouth end of the doffer-nozzle parallel with the face of the card-clothing of the doffer in all positions of adjustment of such nozzle toward and from the doffer.

By way of completing the illustration I have shown the suction-pipe 14 connected with the three-way piece 13 by means of an L-shaped fitting or coupling-member 20, Fig. 1, which is attached to the suction-pipe. The three-way piece is formed at its top with an outlet opening 21, Fig. 3, around which

is a depressed seat 22 that receives the free end of said coupling-member. The said end is held within the said seat by means of a screw 23 screwing into a threaded hole in the top of the three-way piece and engaging by its outwardly extending flanged head over an annular shoulder 24, Fig. 1, on the exterior of such end.

The cylinder-nozzle and doffer-nozzle, respectively, are connected detachably with the three-way piece, this detachable connection rendering them replaceable by others having mouths of different sizes and widths.

For the connection of the cylinder-nozzle with the three-way piece, the latter is furnished in conjunction with one of its inlet-passages with a tubular socket, 24, within which the butt-end of said nozzle fits. The said socket is slotted longitudinally at 25, at its free end and for a distance therefrom, and thereby is rendered expansible and contractible. It is furnished with means for contracting it upon the inserted end of the cylinder-nozzle, such means comprising in this instance a screw 26 working in lugs 27, 27, with which the socket is furnished at opposite sides of the slit 25. The cylinder-nozzle may be adjusted lengthwise with relation to socket 24, to vary the closeness of approach of its mouth to the surface of the card-clothing of the cylinder 1.

For the connection of the doffer-nozzle with the three-way piece, the latter is formed at the outer end of one of its inlet-passages with a flat face against which a flat face of the butt-end of the doffer-nozzle is fitted, laterally-projecting lugs 271, 271, being provided upon the three-way piece and the said butt-end, respectively, which lugs are engaged by screws 28, 28, serving to bind the doffer-nozzle to the three-way piece with the contacting faces of both thereof pressed firmly together.

The socket 24 is shown as formed in a piece separate from the three-way piece, and connected with a rearward extension of the latter by means of a vertical pivot 29. This hinging of the socket to the three-way piece by such pivot enables the cylinder-nozzle to be swung laterally from its working position in Fig. 1 to a position parallel with and close to the traverse-tube 9, substantially at right angles with the said working position. See Fig. 4. This provides for withdrawing the free end of the cylinder-nozzle from slot 31 in cover 3, as for example in order to enable said cover to be moved into an open position or removed. It provides also for locating the cylinder-nozzle in an idle position, out of the way, when the stripper-attachment is not in use, as for instance while the cylinder card-clothing is being ground. For the purpose

of retaining the cylinder-nozzle in its working position when required, keeper-devices are provided. Such devices include in this instance a screw 30, Figs. 3 and 4, having one end thereof located between upper and lower lugs 31, 31, on the three-way piece, the said screw being pivoted to the three-way piece by means of a pin 32. The socket 24 is provided with a pair of lugs 33 between which the screw is adapted to enter as it is swung around into the position occupied by it in Fig. 3. A washer 34 and thumb nut 35 are mounted upon the threaded portion of the screw. By tightening up the wing-nut to press the washer against the backs of the lugs 33 the socket may be locked in place with a cylinder-nozzle 80 extending from the three-way piece in working position, with its mouth-portion within slot 31 in door 3. Upon backing-off the wing-nut, the clamping screw 30 may be swung around so as to carry the washer and wing-nut outward free of the lugs 33, thereby unfastening the socket so as to leave the latter and the cylinder-nozzle free to be swung around laterally. This feature of hinging the socket and cylinder-nozzle to permit them to be swung laterally out of and into working position forms no part of the present invention.

What is claimed as the invention is:—

1. A vacuum-stripper attachment for carding engines, comprising, in combination, a traversing carriage having a positioning and guiding face, a suction-box having adjustment slots and a face adapted to fit against said positioning and guiding face, a suction-nozzle combined with said suction-box, and screws occupying said slots for holding said faces clamped together with capacity for adjustment of the suction-box to locate the mouth of the nozzle at the required working distance from the face of the card-clothing of the cylinder which is to be stripped.

2. A vacuum-stripper attachment for carding engines, comprising, in combination, a traversing carriage having a positioning and guiding face, a suction-box having adjustment-slots and a face adapted to fit against said positioning and guiding face, a suction-nozzle combined with said suction-box, screws occupying said slots for holding said faces clamped together with capacity for adjustment of the suction-box to locate the mouth of the nozzle at the required distance from the face of the card-clothing of the cylinder which is to be stripped, and guiding means whereby the mouth of the nozzle is kept parallel with the said face of the card-clothing.

ERNEST CLARK.
